(No Model.)

R. S. CATHCART.
OIL EXPRESSING BOX.

No. 320,847.

Patented June 23, 1885.

UNITED STATES PATENT OFFICE.

RODNEY S. CATHCART, OF PALESTINE, TEXAS, ASSIGNOR TO THE AMERICAN COTTON OIL COMPANY, OF ST. LOUIS, MISSOURI.

OIL-EXPRESSING BOX.

SPECIFICATION forming part of Letters Patent No. 320,847, dated June 23, 1885.

Application filed March 23, 1885. (No model.)

To all whom it may concern:

Be it known that I, RODNEY S. CATHCART, of Palestine, Texas, have made a new and useful Improvement in Oil-Expressing Boxes 5 for Expressing the Oil from Cotton-Seed and other Seeds, of which the following is a full, clear, and exact description.

The object of the improvement is to provide means for obviating the use of mats in 10 oil-expressing boxes.

It consists, mainly, in the mode of constructing the follower. Heretofore in constructing oil-expressing boxes it has been customary to provide for a certain amount 15 of play between the follower and the box, and to prevent the folds of the bag which contains the material from which the oil is expressed from being caught between the follower and the sides of the box, guard- 20 strips have been attached to the follower at its upper side edges, which serve to close the joints between the follower and the sides of the box.

In the present construction the follower is 25 adapted to fit the box, so as to obviate the need of any joint-closing device, and the face of the follower at its side edges is raised to better confine the bag in place, and at its center or central portion is channeled and provided with a false bottom to provide for the escape of the oil.

The annexed drawings, making part of this specification, illustrate the improved box.

Figure 1 is a plan of the box. Fig. 2 is 35 a bottom view. Fig. 3 is a vertical longitudinal section on the line 3 3 of Fig. 1, and Fig. 4 is a vertical transverse section on the line 4 4 of Fig. 1. The view shows two boxes.

40 The same letters of reference denote the same parts.

Otherwise than as modified by the improvement the box A is constructed in the usual manner.

45 B represents the follower of the box, and C the chamber or box proper in which the follower works. The follower, in width, is made to work as snugly as is practicable within

the chamber C, its sides *b b* coming close to the customary lining-strips *c c*, which constitute the sides of the chamber. The elevation of the side edges is shown at *b' b'*. The oil-channels *b²* extend longitudinally in the follower-face, and they are covered by the perforated plate *b³*, which, when used, constitutes, with the raised edges *b' b'*, the support for the bag. The roof of the chamber C is preferably similarly constructed, it being inclined or curved downward at its side corners, *c' c'*, and end corner, *c²*, channeled 55 longitudinally at *c³*, and provided with the perforated plate *c⁴*, which serves to inclose the channels *c²*, and with the depressed corners *c' c²* to constitute the ceiling of the chamber C. 65

There may be one or more rounded ribs, D, extending along the ceiling of the chamber C, to facilitate the removal of the compressed bag and its contents from the chamber. There may be the customary oil-channels *a a* behind 70 the lining-strips *c c*.

I claim—

1. An oil-expressing box, whose follower is fitted to the chamber C, and whose edges are raised at *b' b'*, substantially as and for the 75 purpose described.

2. An oil-expressing box follower, whose face is channeled and provided with a perforated plate, substantially as described and for the purpose set forth. 80

3. An oil-expressing box follower, whose face is channeled at *b²* and provided with the perforated plate *b³*, and having the raised edges *b' b'*, in combination with the chamber C, substantially as described. 85

4. An oil-expressing box, the ceiling of whose chamber C is channeled and provided with a perforated plate, as and for the purpose described.

5. An oil-expressing box, the ceiling of 90 whose chamber C is provided with a rib or ribs D, as and for the purpose described.

6. An oil-expressing box, the ceiling of whose chamber C is channeled, in combination with the channeled follower B, substantially as described. 95

7. An oil - expressing box, the ceiling of whose chamber C is channeled, as and for the purpose described.
8. An oil - expressing box, the ceiling of whose chamber C is channeled and provided with the perforated plate, in combination with the follower B, whose face is channeled
- and provided with the perforated plate and having the raised edges, substantially as described.

RODNEY S. CATHCART.
